[57] CLAIM

The ornamental design for a waist clip for physical exerciser, substantially as shown and described.

DESCRIPTION

FIG. 1 is a perspective view of a waist clip for physical exerciser showing my new design;
FIG. 2 is a front elevational view thereof;
FIG. 3 is a rear elevational view thereof;
FIG. 4 is a top plan view thereof, the bottom plan aspect being substantially a mirror image;
FIG. 5 is a left end elevational view thereof; and
FIG. 6 is a right end elevational view thereof.
